MACHINE FOR PACKING CELERY BUNCHES
IN TRENCHES

Arvil Towe, Mountain Grove, Mo.

Application December 6, 1947, Serial No. 790,155

4 Claims. (Cl. 214—1)

1

This invention relates to what might be termed a "celery plunger." In the production of "pascal" celery, the celery plants are grown to substantially full maturity in bunches. These bunches are then placed in a long, straight trench in the ground and covered with earth. The new shoots of celery start from the roots of each bunch in the trench. Months later the trenches are opened and the original celery bunches are discarded. The new shoots are gathered and placed on the winter market, thus producing the much more tender celery with perfectly bleached stalks, known to the trade as "pascal" celery.

The bunches are usually dropped into the trench by hand, and each bunch is kicked against the bunches already in the trench to pack the bunches tightly therein. This is a rather slow, tedious, and tiresome process.

The principal object of this invention is to provide a machine which will push each incoming bunch of celery against the other bunches in the trench, and which will utilize the pushing reaction to drive the machine along the trench, thus eliminating the manual labor and insuring a uniform pressure on, and a close packing of, the bunches.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved celery plumping machine, illustrating it in place in a curing trench, with the near wheel removed for illustrative purposes;

Fig. 2 is a plan view thereof; and

Fig. 3 is a detail, cross-section, taken on the line 3—3, Fig. 2.

In the drawings, the ground surface is indicated at 17, and a celery curing trench is indicated at 16.

The invention comprises a substantially rectangular, horizontal frame 10 supported upon a pair of rear wheels 11 and a single front guide wheel 12. The rear wheels 11 are widely spaced from the frame 10 upon axle brackets 13 and ride upon the ground surface 17 at each side of the trench 16. The front wheel is carried in a fork 14 which is rotatably mounted in a sleeve

2

15 welded or otherwise secured to the front of the frame 10.

A guiding yoke 18 is hinged to the fork 14 and extends forwardly therefrom. The yoke has a width substantially equal to the width of the trench 16. The fork 14 has a length sufficient to place the front wheel 12 on the bottom of the trench 16 when the frame 10 is in a substantially horizontal position thereover.

The rear wheels 11 are at an elevation to ride upon the ground surface 17 when the frame 10 is horizontal. As the machine moves forward, the yoke 18 engages the sides of the trench and guides the front wheel 12 along the middle of the trench.

A celery box 19 consisting of two sides and a bottom and having an open top, front, and back, is drawn behind the frame 10 by means of a pair of pull rods 20, which are pivotally secured to the forward extremity of the frame and extend rearwardly to hinge bolts 21 on the sides of the celery box.

The box has a width to fit closely into the trench 16 so that it may be drawn therealong. A plunger plate 22 is reciprocally mounted in the box 19. The plunger is fixedly mounted on the rearward extremities of the two reciprocating guide rods 23. The rods 23 slide in guide sleeves 24, which are welded or otherwise secured to the inner faces of the two sides of the box 19.

The plunger plate 22 is reciprocated by means of a connecting rod 25 which extends from a hinge clip 26 on the plunger plate forwardly and upwardly to a crank on a crank shaft 27. The crank shaft 27 is mounted in bearing boxes 28 on the frame 10 and is rotated from a suitable gas engine 29 through any type of speed reduction mechanism.

The speed reduction mechanism employed in the embodiment illustrated comprises a counter-shaft 30 carrying belt pulleys 31. The crank shaft 27 also carries a belt pulley 32. Endless belts 33 extend between the pulleys and round a drive pulley 34 on the engine 29 to transmit rotating power to the crank shaft 27 at reduced speed.

In use, the front wheel 12 and the box 19 are placed in the trench 16, with the wheels 11 spanning the trench. The engine is started and a celery bunch, indicated at 35, is dropped in the box 19 to the rear of the plunger plate 22. Rotation of the crank shaft causes the plunger plate to push this bunch rearwardly against the packed celery bunches in the trench. The reaction of the rearward push causes the entire machine to move forward a distance equal to the width of

that bunch of celery. The plunger plate 22 then again moves forward and another bunch of celery is dropped behind it and is similarly pushed against the aligned, packed celery. This operation continues throughout the entire length of the row.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A device for packing celery in a trench, comprising: a supporting frame; wheels supporting said frame above said trench; a U-shaped box riding in said trench; hinged link members connecting said box with said frame; a plunger positioned to travel longitudinally of said box; means for reciprocating said plunger; and guiding means on the forward extremity of said frame, said guiding means riding in said trench to guide the frame along the trench at each reciprocation of said plunger.

2. A device for packing celery in a trench, comprising: a substantially horizontal frame; a rear axle member extending across said frame; a rear wheel at each extremity of said axle adapted to travel upon the ground surface at each side of said trench to support the rear extremity of said frame; a front wheel fork rotatably mounted beneath the forward extremity of said frame; a front wheel mounted in said fork and adapted to ride in the bottom of said trench; means extending from said fork into contact with the side walls of said trench for guiding said front wheel along said trench; a celery-receiving box positioned in the bottom of said trench below said frame, said box having an open top and an open rear end; a plunger arranged to move longitudinally of said box to force celery bunches from said open rear end; and means carried by said frame for reciprocating said plunger.

3. A device for packing celery in a trench, comprising: a substantially horizontal frame; a rear axle member extending across said frame; a rear wheel at each extremity of said axle adapted to travel upon the ground surface at each side of said trench to support the rear ex-

tremity of said frame; a front wheel fork rotatably mounted beneath the forward extremity of said frame; a front wheel mounted in said fork and adapted to ride in the bottom of said trench; means extending from said fork into contact with the side walls of said trench for guiding said front wheel along said trench; a celery-receiving box positioned in the bottom of said trench below said frame, said box having an open top and an open rear end; a plunger arranged to move longitudinally of said box to force celery bunches from said open rear end; connecting means suspending said box from said frame so that the former will move with the latter; a crank shaft on said frame; a connecting rod between said crank shaft and said plunger to reciprocate the latter; and means carried by said frame for rotating said crank shaft.

4. A device for packing celery in a trench, comprising: a substantially horizontal frame; a rear axle member extending across said frame; a rear wheel at each extremity of said axle adapted to travel upon the ground surface at each side of said trench; a steerable front wheel on said frame adapted to ride in the bottom of said trench; means connected with said front wheel and adapted to contact the side walls of said trench for guiding said front wheel along said trench; a celery-receiving box positioned in the bottom of said trench below said frame, said box having an open top and an open rear end; a plunger arranged to move longitudinally of said box to force celery bunches from said open rear end; connecting means suspending said box from said frame so that the former will move with the latter; guide means in said box for supporting and guiding said plunger; a crank shaft rotatably mounted on said frame; a connecting rod extending from said crank shaft to said plunger; and means carried by said frame for rotating said crank shaft.
